UNITED STATES PATENT OFFICE.

FRANK G. McMILLAN AND HOWARD O. McMILLAN, OF MINNEAPOLIS, MINNESOTA.

METALLIC INSERT.

1,240,993.

Specification of Letters Patent. Patented Sept. 25, 1917.

Application filed May 22, 1916. Serial No. 99,149.

To all whom it may concern:

Be it known that we, FRANK G. McMILLAN and HOWARD O. McMILLAN, citizens of the United States, residing at Minneapolis, in 5 the county of Hennepin and State of Minnesota, have invented certain new and useful Improvements in Metallic Inserts; and we do hereby declare the following to be a full, clear, and exact description of the invention, 10 such as will enable others skilled in the art to which it appertains to make and use the same.

Our invention has for its object to provide an improved metallic wall insert adapted 15 for use to anchor nut-equipped bolts to concrete walls or slabs; and to such ends, generally stated, the invention consists of the novel construction and combination of parts hereinafter described and defined in 20 the claims.

In the accompanying drawings which illustrate the invention, like characters indicate like parts throughout the several views.

25 Referring to the drawings:

Figure 1 is an end elevation of the improved wall insert showing the same attached to one of the boards upon which a concrete floor is to be formed;

30 Fig. 2 is a longitudinal section on the line $x^2 x^2$ of Fig. 1;

Fig. 3 is a section on the line $x^3 x^3$ of Fig. 2;

35 Fig. 4 is a transverse vertical section taken approximately on the line $x^4 x^4$ of Fig. 5, showing the insert embedded within the concrete floor;

Fig. 5 is a section on the line $x^5 x^5$ of Fig. 4; and

40 Fig. 6 is a perspective with some parts broken away, showing the tubular body of the insert.

In Figs. 1, 2 and 3, the numeral 1 indicates one of the boards of a temporary 45 wooden floor upon which the concrete floor is to be formed, and in Figs. 4 and 5, the numeral 2 indicates a concrete floor in which the insert is embedded. The numeral 5 indicates a bolt provided with a nut 6, which nut, 50 as shown, is of the square or rectangular type. The body 7 of the insert is of tubular form, but is provided with a long slot 8 that runs, preferably from end to end thereof. This tubular body may be made in different ways, but is preferably rolled from a

flat piece of sheet steel. It may be made in any desired length and is adapted to be embedded in the concrete of the wall or floor. Its form is such that when it is embedded, it will, even without additional anchoring 60 means, be quite securely anchored in the concrete. However, it should be further anchored by additional devices which also close the ends of the tube and prevent the concrete from entering except at the very ends 65 of the tube. For short tubes, only two anchors will be provided and each would be in the form of a disk 9 having a flat flaring tail portion 10. In order that the disks 9 can be inserted into the ends of the tube, the 70 latter is formed with notches 11, and preferably, also, with intervening clenching lips 12, which latter are adapted to be inserted through perforations in the tail portion 10. When the disks 9 are inserted into the ends 75 of the tube with the lips 12 projected through the perforations thereof, and the said lips are then clenched or bent over, as best shown in Figs. 1, 2 and 5, the disks and their tails will be securely locked to the 80 ends of the said tube with the disks set in considerably from the extreme ends of the tube. As a simple and efficient means for temporarily securing the insert to one of the boards 1, the disks 9 are provided with laterally bent ears 13 having perforations 85 through which nails 14 may be driven into the board 1, as shown in Fig. 2.

For long insert tubes, one or more intermediate anchors, such as best shown in Fig. 90 3, but also indicated in the other views, may be employed. This intermediate anchor is formed from a piece of sheet metal 15 stamped to form diverging legs and having a circular opening through which the 95 tube can be telescoped. The tube is, of course, placed so that its slot 8 will be flush with the surface of the concrete slab or wall and in line with the said slot 8, and the perforation in the anchor 15 through which the tube is passed will be left open so that said anchor will not interfere with lateral sliding movements of the bolt 5 within the slot 8.

Preferably, the slot 8 will be of such width 105 that the nut 6 may be inserted edgewise through the same. Obviously, when the nut is inserted and turned parallel to the plane of the slot, it will engage the tube, as best shown in Fig. 4, so that the threaded end 110

of the bolt may be then screwed through the nut and the nut will be anchored against the tube.

When the tube and the anchors are embedded in the concrete, the said tube will be very firmly and rigidly secured in the concrete slab, and its walls will be reinforced by the concrete, so that they will have great strength, even when the tubular insert is made of comparatively thin metal. Obviously, the bolt may be applied at any desired place within the slot 8, so that a large range of adjustment is provided for and it is not necessary to set the insert with great accuracy. Obviously, increased length of the tubular insert will add but very slightly to the cost thereof, inasmuch as the end anchors will be of the same form in all cases. The end anchors and the intermediate anchors may be applied to the tube, either before shipment, or at the place where they are to be put up. If applied before shipment and the lips 12 turned over, all of the composite parts of the insert will be connected and ready for use. As shown, and preferably, the tubular insert is made cylindrical in cross section, but its form may, of course, be varied.

The cylindrical form, however, is best, because when it is embedded in the concrete with its rod exposed at one surface thereof, it will be held by the concrete with a sort of a dove-tailed action even where special anchors are not provided and will, in fact, be so firmly held by the surrounding concrete that it will not be pulled from position without tearing away a very considerable part of the concrete body.

What we claim is:

40 1. A wall insert comprising a metal tube normally open at its ends, provided with a longitudinal slot and provided with end notches opposite its slot, and disks inserted into the ends of said tube, and having anchoring portions projecting through said end notches and adapted to be embedded in the concrete.

50 2. A wall insert comprising a metal tube having open ends and a longitudinal slot, and metal disks insertible into the ends of said tube and having interlocking engagement therewith and provided with projecting anchor portions adapted to be embedded in the concrete, the said disks further hav-

ing laterally projecting ears alined with the slot of said tube and adapting the insert to be temporarily secured to one of the boards of the concrete form.

3. A wall insert comprising a metal tube normally open at its ends, provided with a longitudinal slot and provided with end notches opposite its slot, and disks inserted into the ends of said tube, and having anchoring portions projecting through said end notches and adapted to be embedded in the concrete, the said disks having outwardly projecting ears alined with the slot of said tube and adapting the insert to be temporarily secured in one of the boards of the concrete form. 70

4. A wall insert comprising a metallic tube normally open at its ends, provided with a longitudinal slot, and having end notches and intervening clencher lips opposite said slot, and metal disks inserted into the ends of said tube, said disks having perforations through which said lips are passed and clenched, and further having anchoring portions projecting through the said end notches adapted to be embedded in the concrete. 75

5. A wall insert comprising a metal tube having open ends and a longitudinal slot, metal disks engageable with the ends of said tube and having projecting anchor flanges, 85 and an intermediate anchor plate embracing the intermediate portion of said tube and adapted to be embedded in the concrete.

6. A concrete insert comprising a metallic tube having a longitudinal slot adapted to be exposed at the surface of a concrete body, said tube being normally open at its ends, and anchoring heads having interlocking engagement with the normally open ends of said tube, and substantially closing said ends 95 when applied, said heads having projecting anchors extended therefrom in a direction away from the slot of said tube, the points beyond the back of said tube, and adapted to be embedded in the concrete. 100

In testimony whereof we affix our signatures in presence of two witnesses.
